UNITED STATES PATENT OFFICE.

AUGUST MAYER, OF PASADENA, CALIFORNIA.

AUTOMATIC FLUSH-TANK.

SPECIFICATION forming part of Letters Patent No. 426,033, dated April 22, 1890.

Application filed January 27, 1890. Serial No. 338,263. (No model.)

To all whom it may concern:

Be it known that I, AUGUST MAYER, a citizen of the United States, residing at Pasadena, in the county of Los Angeles and State of California, have invented a new and useful Improvement in Automatic Flush-Tanks, of which the following is a specification.

My invention relates to that class of flush-tanks which discharge at regulated intervals through a siphon.

One purpose of my invention is to provide cheap and simple mechanism whereby the discharge is produced by positive and direct mechanical action, so as to avoid any liability of failure to act properly, also to avoid the necessity of great accuracy in setting the tank.

A further object is to so construct the flush-tank that when it is used for sewers it can be set at any desired depth in the earth above the sewer, thereby avoiding the expense of constructing unnecessarily deep tanks to flush deep sewers.

My invention primarily consists of the combination of the reservoir of the flush-tank, a plain vertical discharge-pipe having its lower end sealed, extending upward through and projecting above the floor of the reservoir, a vertically-movable siphon-bell or intaking limb inverted over such pipe, a supply of water flowing into such reservoir, the water seal at the bottom of the pipe, and mechanism adapted to be operated by the rising water within the reservoir to suddenly elevate the siphon-bell when the water rises to the top of the pipe, whereby the water within the bell at the top thereof is suddenly precipitated into the pipe to start the siphonage. In practice the bell is provided with siphon-breaking mechanism, as hereinafter set forth.

My invention as illustrated comprises the combination of a flush-tank reservoir, a supply of water flowing thereinto, a vertical discharge-pipe extending upward from the bottom of the reservoir and having its lower end sealed, a vertically-moving siphon-bell or intaking limb inverted over the discharge-pipe, a float arranged to raise such bell by its buoyancy when the water in the tank approximately reaches the top of such pipe, means for maintaining a pressure to depress such float, and means for relieving such press-

ure suddenly when the buoyancy of the float raises the bell.

Various forms of mechanism have been devised by me to carry out this invention; but I consider the mechanism illustrated in the accompanying drawings to embody the best mode of applying the principle of my invention.

Figure 1 is a vertical mid-section of a flush-tank embodying my invention. Fig. 2 is a view of the upper portion of the siphon-starting mechanism. This view is taken at right angles to that of Fig. 1. Fig. 3 is a perspective top view of the siphon starting and breaking mechanism. Fig. 4 is a detail of part of the mechanism.

A is the reservoir, from the floor of which projects upward the discharge-pipe B, communicating with the conduit or outlet C to be flushed. This pipe is of any desired length, and its lower end extends downward through the floor of the reservoir and into the sealing-basin D below the bottom of the outlet, so that when such basin is filled with water the pipe will be sealed thereby at its lower end.

The pipe B or discharge-limb of the siphon projects above the floor of the tank to the height required to allow the accumulation of sufficient water to perform the flushing desired. This pipe may be made of sewer-pipe; or it may be of iron or any other desirable material. The bell or intaking limb E of the siphon is provided at its upper end with a float F, and is provided near its lower end with an auxiliary member G, having its bottom above the bottom of the bell. The member G communicates with the interior of the bell through perforation H near the top of the auxiliary member. The bell is suspended from one arm of a balance-lever I, which is journaled at a point in its mid-length to rotate upon axis J, which is secured to the reservoir-wall and projects over the bell from the wall at one side of the reservoir. The pivoted balance-lever I is bent and one of its arms is weighted and the other arm is pivotally connected with rod K, by which the bell is suspended. Lugs L M project, respectively, from the lever I and axis J, and are arranged to interfere with each other when the bell is at its lowest position. The solid lines in Fig. 1 show the bell in its depressed position.

tion ready to be raised by the buoyancy of the float when the water rises, as is hereinafter described. The balance-lever is pivotally connected with the bell and is provided with a weighted arm, and is so arranged that when the bell is in its depressed position the center of gravity of the weighted arm will fall between its pivoted axis J and the pivotal pin U, which supports the bell, so that the tendency of the weight is to hold the bell in its depressed position.

The water-supply pipe N is provided with a cock O, which is arranged to discharge water into ventilator-pipe P, which opens into the conduit to be flushed. The bottom of such conduit slopes downward from such ventilator-pipe to the sealing-basin, so that in preparing the tank for operation the seal can be conveniently formed by opening cock O until sealing-basin D is filled. When the basin D is filled, the cock O may be shut, or it may be left sufficiently open to admit enough water into the sealing-basin to supply any loss from possible leakage. The tank is now ready for operation.

The operation is as follows: Cock Q is opened to discharge the quantity of water required and the tank slowly fills. The water rising at the same time in intaking limb or bell E forces the air from such limb out through the seal at the bottom of pipe B. When the water has risen almost to the top of pipe B, the buoyancy of the float causes the bell to rise, thus operating the balance-lever to throw the weight S onto the side of the axis J opposite that from which the bell-supporting arm R projects. When the center of gravity passes over the axis J, the statical momentum of the weight operates to diminish the pressure upon the float, which rapidly rises, lifting the bell into the position shown by the dotted lines in Fig. 1, thus suddenly precipitating a large quantity of water into pipe B and starting the siphon at once. When the water is drawn out of the tank to the level of the bottom of the auxiliary member G the water in G will flow up through perforation H until G is emptied. Air will then flow through the perforation into F, and thus break the siphonage. When by the lowering of the water in the tank the buoyancy of the float has been diminished to such extent that the statical momentum of the bell and its attachments exceeds that of the weight S, the bell will fall back into its original position, as shown in the solid lines in Fig. 1, after which the operation is repeated as before. The rush of water caused by this mechanism is so great that the extent of the seal is not an important factor in the operation, and good results are secured whether the seal is heavy or light. Since the connection between the reservoir and the conduit to be flushed is a straight plain pipe and may be of any desirable length, the reservoir can be placed near the surface of the ground only deep enough to protect the

water from freezing. The pipe P allows the warm air from the sewer to enter the reservoir to keep the temperature of the water 70 above freezing-point.

V represents the supply of water flowing into the reservoir.

The bell and float and auxiliary member can be conveniently cast of one piece of 75 metal. The float being formed, as shown in the drawings, of a cylinder open at the bottom and closed at the top, surrounding and connected with the bell, the rising water closes the mouth of the float and prevents 80 the escape of air. If desired, however, the bell and float may be made of galvanized iron, and the float may be closed at the bottom; or it may be constructed separate from the bell and be connected therewith by various means, which will readily suggest themselves to those skilled in the art. I do not wish to be limited to the specific construction shown in the drawings; but

What I claim as new, and desire to secure 90 by Letters Patent, is—

1. The combination of the reservoir, a plain vertical discharge-pipe having its lower end sealed, extending upward through and projecting above the floor of the reservoir, a vertically-moving siphon-bell inverted over such pipe, a supply of water flowing into the reservoir, the seal at the bottom of the pipe, and mechanism adapted to be operated by the rising water within the reservoir to suddenly 95 elevate the siphon-bell when the water rises to the top of the pipe.

2. In a flush-tank, the combination of the reservoir, a supply of water flowing thereinto, a vertical discharge-pipe extending upward from the bottom of the reservoir and having its lower end sealed, the seal, a vertically-moving siphon-bell inverted over the discharge-pipe, a float arranged to raise such bell by its buoyancy when the water in the 105 tank reaches the top of such pipe, means for maintaining a pressure to depress such float, and means for relieving such pressure suddenly when the buoyancy of the float raises the bell.

3. In a flush-tank, the combination of the reservoir, a supply of water flowing thereinto, the discharge-pipe projecting upward from the floor of the reservoir and extending downward through such floor and sealed at 110 its lower end, the seal, the inverted bell provided at its upper end with a float, a pivoted balance-lever pivotally connected with the bell and provided with a weighted arm, and so arranged that when the bell is in its depressed position the center of gravity of the weighted arm will fall between its pivotal axis and the pivotal pin which supports the bell.

AUGUST MAYER.
